UNITED STATES PATENT OFFICE.

BENJAMIN P. RICHARDSON, OF BOSTON, MASSACHUSETTS.

SMOKER'S IMPLEMENT.

SPECIFICATION forming part of Letters Patent No. 366,611, dated July 12, 1887.

Application filed November 13, 1884. Serial No. 147,819. (No model.)

To all whom it may concern:

Be it known that I, BENJAMIN P. RICHARDSON, a citizen of the United States, residing at Boston, in the county of Suffolk and State of Massachusetts, have invented certain new and useful improvements in Smokers' Implements; and I do hereby declare that the same are fully described in the following specification and illustrated in the accompanying drawings.

10 The object of my invention is to provide a compact, neat, convenient, useful, and easily-portable article for the use of smokers of tobacco, in the form of a pocket cigar-cutter and pipe cleaner and tamper.

15 My invention is embodied in the implement herein shown and described, and particularly referred to in the appended claims.

In the drawings, Figure 1 is a plan view. Fig. 2 is a plan view of the rear side of the device, showing the blade in a different position; and Fig. 3 is a perspective view of the same.

20 In the larger end of the blade A is a circular perforation, D, of proper size to admit the end of a cigar. The sides of this perforation are beveled outwardly—that is, from the blade B—in order that the tapering end of the cigar when inserted may fit firmly and evenly against the sides of the orifice.

25 The blade B, which is parallel and in contact with the blade A throughout, has at its larger end a double-cutting edge, I, fitting closely to the edge of the opening D, so that when the end of the cigar is inserted in the opening the movement of the blade B in either 30 direction against the cigar cuts off the end at the proper point, leaving a smooth and even surface. This cutting-blade is also adapted to serve as an ink-eraser when required. To the opposite end of the blade A is attached transversely a flat circular disk or tamper, G, of suitable diameter, for the purpose of pressing or tamping down the tobacco in the bowl of a pipe preparatory to or during the act of smoking. The outer face of this disk may be 35 suitably engraved to serve as a letter-seal.

40 The end of the blade B opposite to the cutting end is formed tapering and of proper shape to form (when reversed upon the pivot C, so as to project beyond the blade A) a pick

45 or cleaner, H, for the purpose of loosening and removing from the pipe-bowl any ashes or other accumulation or deposit whenever desired. This projecting end H may be suitably shaped to serve also as a nail-cleaner, and a file-surface, F, may be formed on either blade 50 for the purpose of dressing the nails.

Upon the inner surface of the blade A or B, near its lower end, I form a slight protuberance, E, adapted to fit into a corresponding depression in the adjacent face of the other 55 blade, thus forming an automatic catch to hold the blades in a parallel position when not in use for cutting.

The perforated end of the blade A is made somewhat longer than the cutting end of the 60 blade B, so as to form a protection or shield for the latter when not in use for cutting.

I am aware of the bolt-cutter patent of Whittaker, dated July 25, 1871, No. 117,495, showing a bar having a square opening through 70 it, of uniform diameter, to receive a nut, and a cutting-blade pivoted to said bar and worked by a separate lever and connecting-link, giving a compound leverage. Such an implement would be wholly unsuited to my purposes, and 75 I therefore make no claim thereto; but

I claim as my invention—

1. The implement described and shown, consisting of the blade A, having a circular beveled opening through it, and the blade B, pivoted thereto, having two cutting-edges, in combination with the pivot C, which unites 80 said blades and the automatic catch E, substantially as and for the purpose set forth.

2. The combination of the blades A and B, 85 made of about equal length and pivoted together at C, the short end of the blade B having two cutting-edges, and the corresponding end of the blade A extending in a curved line slightly beyond said edges and serving as a 90 guard for them, substantially as set forth.

In testimony whereof I hereto affix my signature in presence of two witnesses.

BENJ. P. RICHARDSON.
